(57) **CLAIM**

The ornamental design for a barbecue fork, as shown and described.

DESCRIPTION

FIG. 1 is a perspective view of a barbecue fork showing our new design;

FIG. 2 is a side elevational view of the inventive design of FIG. 1;

FIG. 3 is an opposite side elevational view of the design of FIG. 1;

FIG. 4 is a top plan view of the design of FIG. 1;

FIG. 5 is a bottom plan view of the design of FIG. 1;

FIG. 6 is an end elevational view of the design of FIG. 1;

FIG. 7 is an opposite end elevational view of the design of FIG. 1;

FIG. 8 is a perspective view of the fork shown separately for clarity of illustration;

FIG. 9 is a side elevational view of the inventive design of FIG. 8;

FIG. 10 is an opposite side elevational view of the design of FIG. 8;

FIG. 11 is a top plan view of the design of FIG. 8;

FIG. 12 is a bottom plan view of the design of FIG. 8;

FIG. 13 is an end elevational view of the design of FIG. 8;

FIG. 14 is an opposite end elevational view of the design of FIG. 8;

FIG. 15 is a perspective view of the protective sheath shown separately for clarity of illustration;

FIG. 16 is a side elevational view of the inventive design of FIG. 15;

FIG. 17 is an opposite side elevational view of the design of FIG. 15;

FIG. 18 is a top plan view of the design of FIG. 15;

FIG. 19 is a bottom plan view of the design of FIG. 15;

FIG. 20 is an end elevational view of the design of FIG. 15;

and,

FIG. 21 is an opposite end elevational view of the design of FIG. 15.
